UNITED STATES PATENT OFFICE.

PASQUALE URSINO, OF ELLensburg, WASHINGTON.

BALLAST SURFACER.

Application filed September 7, 1920. Serial No. 408,781.

To all whom it may concern:

Be it known that I, PASQUALE URSINO, a citizen of the United States, residing at Ellensburg, in the county of Kittitas and State 5 of Washington, have invented certain new and useful Improvements in Ballast Surfacers, of which the following is a specification.

This invention relates to railway ballast 10 forming machines and, more especially, to improvements in the ballast surfacer illustrated and described in United States Patent No. 1,343,533, issued to me June 15, 1920.

The object of the present invention is the 15 perfecting of the patented apparatus above referred to and the provision of devices supplementary to those disclosed in said patent whereby the uses of the apparatus are extended with an increase in efficiency.

20 The invention consists in the novel construction, arrangement and combination of parts to be hereinafter described and claimed.

In the accompanying drawings, Figure 1 25 is a plan view of apparatus embodying the present invention shown applied to a railway car. Fig. 2 is a view partly in front elevation and partly in transverse section, said section being taken substantially 30 through 2-2 of Fig. 1. Fig. 3 is a front elevational view of Fig. 1, a part of the car frame being shown in transverse section. Fig. 4 is a fragmentary section view through 35 4-4 of Fig. 1. Figs. 5 and 6 are detail sectional views through 5-5 and 6-6 of Fig. 1.

In said drawings, the reference numeral 10 designates the platform of a car having 40 wheels 11 which travel on rails, such as 12, laid upon ties 13. Secured to the rear end 45 of the car platform is a hinge member 14 through which extends, longitudinally of the car, a pin 15 for a complementary hinge member 16 in the form of a depending bar. This bar, in turn, serves as a hinge member 50 with respect to the surfacer frame plate 17 by the provision of apertured lugs 16¹ and 17¹, respectively, on the member 16 and said frame plate and pivotally connected by a substantially vertical hinge bolt 18.

55 Above the hinge pin 15, the member 16 is provided with an upwardly directed arm 19 adapted to receive a tubular extension 20 which serves as a handle whereby an operator upon the car may tilt the frame upwardly to pass over obstructions in the path 55 of the hereinafter described surfacing ap-

pliances. For operation, said frame plate is held in oblique angular relations with respect to the car, as shown in Fig. 1, by means of a draw rod 21 connecting the frame plate 60 with an attachment 22 on the car, as shown.

The frame plate 17 is of a width to extend to approximately the adjacent ends of the ties 13 and is connected to a plate 25 by means of a vertical pin 23 engaging in apertured lugs 17² and 25¹ provided on the respective plates.

The plate 25 has its lower edge 25¹ formed to a curvature corresponding to the desired transverse contour of the ballast. In front 70 of the plate 25 is a curved blade 26 having its lower edge serrated by the provision of teeth 27 whose points are directed downwardly and outwardly from the railway track as shown in Fig. 2, and terminate in 75 a curve which is substantially parallel with and lower than the plate edge 25¹.

The blade 26 is secured in spaced relation to the plate 25 by means of bolts 28 extending through distance pieces, such as 29, 80 Fig. 5.

30 represents a reinforcing bar provided on the rear side of plate 5 to afford requisite stiffness to the same. 31 represents a gutter-mold blade in the nature of an extension to the frame plate 25 and is rigidly secured thereto. The frame plate 17, above mentioned, has hingedly connected to its under edge a plurality of sections 32 which are adapted to be swung rearwardly upon 90 encountering the ties 13 and in opposition to springs 33.

The lower ends of the sections 32 are provided with teeth 34 for digging into the material between successive ties in the forward 95 travel of the car.

In the present invention, I provide in front of the frame plate 17 a plowshare in the nature of an approximately rectangular plate 35 which is disposed in substantially 100 the angular relations with respect to the car in which it is shown in Fig. 1.

The upper portion of the plowshare is curved forwardly as at 35¹ and at the bottom it is curved rearwardly as at 35², see 105 Fig. 6.

The curved portion 35², moreover, is formed as shown in Fig. 4 to provide a plurality of share harrow elements 36 disposed to be parallel or nearly so with the 110 track.

Said plowshare is connected to a tri-

angular shaped bracket frame 38 which is rigidly secured to the frame part 17, said plowshare being arranged for vertical movements by means of bolts 39 (Fig. 6) extending through vertical slots, as 40, provided in bracket frame 38 between the plowshare and bearing plates, as 41, which are juxtaposed with the bracket frame.

10 Springs such as 42, Figs. 4 and 6, act to yieldingly retain the plowshare 35 in its lowermost position whereat the bottom of the plowshare will extend below the plane of the top surfaces of the ties. By such an arrangement the plowshare in its forward 15 travel with the car serves to displace material from above and between the ties into the path of the toothed scraper blade 26.

When encountering a tie the curved part 20 of the plowshare serves to elevate the same to enable it to ride over the tie.

The harrow elements above referred to act as a rake for removing large bodies, as rocks or dirt, from the path traveled over by the plowshare.

25 Located in front of the frame part 17 in approximately parallel relations therewith is a scraper blade 43 which is hingedly connected at 44 to bracket arms secured to the bracket frame 38. The lower edge of the 30 scraper blade is, like the plowshare, curved so as to be elevated in opposition to a spring 45 when engaging a tie. The scraper blade 43 acts supplemental to the plowshare for removing material from between the ties.

35 To the rear of the frame part 17 see Fig. 4 are successively positioned a surfacing scraper bar 46 and a brush 47 which are arranged parallel with the ties. The scraper bar 46 is carried by arms 46¹ hinged to ears 40 protruding from frame part 17 to afford vertical movements to the scraper bar. This bar is formed, as shown in Fig. 4, with a substantially horizontal flange element 48 having a concavity in its underside and extending rearwardly from a rounded shoulder 49. The rear edge of the flange element 45 acts to smooth the surface of the material between ties and the function of the shoulder 49 is to impart a lifting movement to the bar when engaging a tie so that the bar may pass thereover.

A spring 51 serves to yieldingly retain said scraper bar in its lowermost position.

The brush 47, which is shown as secured 55 to the arm 52, functions to sweep dirt from the top of the ties and also smooths the surfaces between the ties in following the scraper bar 46.

60 In operation, the plowshare 35 serves to remove material of all sizes from the ties and spaces intermediate therefrom into position in front of the frame plate 25, the toothed blade 26 and surfacing edge of the plate thereupon respectively raking and surfacing the ballast during the travel of the

apparatus forwardly as denoted by direction arrow in Fig. 1.

Any material left by the plowshare on or between the ties is subjected to the action of the scraper 43, the teeth 34, the scraper bar 46 and finally to the brush 47, which act to finish the surface of the material between the ties below the plane of the upper surfaces of the ties in a pulverized and smooth condition. The brush furthermore serves to 75 sweep any dirt from the ties into the spaces there in front.

Included in the invention is a second plowshare in the nature of a plate 53 rigidly secured to bracket arms 54 extending forwardly from the plate 25 and is also secured by stay rods 55 extending forwardly to the car attachment 22.

53¹ represents a gutter-mold plate illustrated as a removable extension to the 85 plate 53.

The plate 53 is disposed in substantially the position in which it is shown in Figs. 1 and 3, with respect to the car and to the plow share 35, that is to say—the outer end 90 of the plate 53 is foremost and its inner end is located in front of the plowshare 35.

The lower edge of plate 53 and its extension 53¹ are serrated to provide teeth 56 and 56¹ whose points are in lines corresponding, respectively, with the contour of the ballast and gutter. These teeth are furthermore directed toward the track and are designed to break the ballast and gutter surfaces in advance of the grading and surfacing devices above described and also to cut vegetation to destroy the same.

The ground when thus broken by the teeth 56, 56¹ is by reason of the angular position of the plate 53 guided upwardly and 105 inwardly toward the track to effect the filling of hollows in the ballast surface up to the contour line as defined by the points of teeth 56, 56¹.

Any surplus material remaining after 110 filling such hollows, either passes over the inner portion of the plate 53 to be treated by the surfacing blade 26, or is delivered beyond the inner end of the plate to the plowshare 35.

To enable the material to pass, as above mentioned, over the inner portion of plate 53, such portion is made to a relatively small elevation to afford a way 57 (Fig. 3) by bending the upper part of the plate 120 down as at 58.

It is to be noted, in contradistinction to the plow 35, and the plate 25, that the plate 53 serves to move the material uphill or toward the track. The plate 53 is peculiarly important in affording a means for distributing material to be subsequently surfaced by the parts of the apparatus to the rear thereof, and also for cutting weeds in resurfacing a track ballast.

What I claim, is,—

1. In apparatus of the character described, the combination with ballast grading and surfacing devices including a frame 5 adapted to be connected to the side of a car, of vertically movable means carried by said frame for progressively grading material between the successive railway ties to a surface below the plane of the upper surfaces 10 of the adjacent ties.

2. In apparatus of the character described, the combination with ballast grading and surfacing devices including a frame 15 adapted to be connected to the side of a car, of a plurality of independently movable devices for digging material between the railway-ties, springs for yieldingly retaining said devices in operative positions, vertically movable means carried by said 20 frame for progressively grading the material dug by said devices to surfaces below the planes of the upper surfaces of the successive railway ties, and means for sweeping material from the upper surfaces of 25 said ties.

3. In apparatus of the character described, the combination with a railway track, and car mounted thereon, of ballast grading and surfacing devices carried by 30 said car at the side of the latter and one in

front of the other, the lower edges of said devices being serrated to provide teeth, the teeth of the forward of said devices being directed toward the track and the teeth of the other device being directed from the 35 track.

4. In apparatus of the character described, a car, means carried thereby for grading the ballast between the ties of the car track to a surface below the plane of the 40 top surfaces of said ties, said means in travelling with the car being arranged to be elevated by the successive ties to pass over the same.

5. In apparatus of the class described, a 45 car, a frame carried thereby above the ties at one side of the car track, a plowshare supported by said frame obliquely of the track for removing material from the track ties, and means carried by said frame in 50 substantially rectangular relations to said ties for grading the material intermediate said ties to a surface below the plane of the top surfaces of the ties.

Signed at Ellensburg, Washington, this 55
28th day of August, 1920.

PASQUALE URSINO.
